(57) **CLAIM**

The ornamental design for a charging case for controller, as shown and described.

DESCRIPTION

FIG. 1 is a front perspective view of a charging case for controller showing our new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is a front perspective view of the charging case for controller of FIGS. 1–7 showing our new design in an alternate state of use;

FIG. 9 is a rear perspective view thereof;

FIG. 10 is a front view thereof;

FIG. 11 is a rear view thereof;

FIG. 12 is a right side view thereof;

FIG. 13 is a left side view thereof;

FIG. 14 is a top view thereof;

FIG. 15 is a bottom view thereof;

FIG. 16 is a front perspective view of a component part of the charging case for controller shown separately for clarity;

FIG. 17 is a rear perspective view thereof;

FIG. 18 is a front view thereof;

FIG. 19 is a rear view thereof;

FIG. 20 is a right side view thereof;

FIG. 21 is a left side view thereof;

FIG. 22 is a top view thereof; and,

FIG. 23 is a bottom view thereof.

The broken lines in the figures depict portions of the article which form no part of the claimed design.

1 Claim, 17 Drawing Sheets
